UNITED STATES PATENT OFFICE.

HERBERT C. RAY, OF SHERIDAN, INDIANA.

PIPE-WRENCH.

No. 928,216.

Specification of Letters Patent.

Patented July 13, 1909.

Application filed September 23, 1908. Serial No. 454,478.

To all whom it may concern:

Be it known that I, HERBERT C. RAY, a citizen of the United States, residing at Sheridan, in the county of Hamilton, State of Indiana, have invented a new and useful Improvement in Pipe-Wrenches, of which the following is a specification.

This invention relates to new and useful improvements in pipe wrenches, the object 10 being to provide a pipe wrench with a pivoted jaw and a pivoted lever, said jaw being connected to the lever by a bowed spring.

A further object of my invention is to provide a head with an adjustable jaw which 15 is operated by a nut, for adjusting the same to suit different size pipes.

A still further object of my invention is to provide a pipe wrench which is so constructed that when placed upon a pipe and the 20 lever forced downwardly it will force the pivoted jaw against the pipe so as to cause the teeth to grip the same more firmly.

With these various objects in view, my 25 invention consists in the novel features of construction arrangement and combination of parts hereinafter fully described, pointed out in the claim and shown in the accompanying drawings, in which—

Figure 1 is a side elevation of my improved 30 pipe wrench the head and yoke being broken away so as to clearly show the pivoted jaw and lever. Fig. 2 is an edge view of my improved wrench, the lever being partly broken away. Fig. 3 is a similar view to that of 35 Fig. 1 showing the wrench in position on a pipe. Fig. 4 is a section taken on line 4—4 on Fig. 1.

In carrying out my improved invention I 40 employ a head member 1 having a yoke portion 1' between which is pivotally mounted the head portion 2' of the lever 2 on a transverse pin 10, said head portion being provided with a beveled end having a recess formed therein in which is seated the angled end of 45 a bowed spring 8, the other end of which fits within the recess formed in the oblique edge of the jaw 7 which is pivotally mounted in the yoke at its forward end on a pivot pin 9 and is provided with a serrated enlarged jaw 50 face 7'. This spring has a tendency to exert a pressure against the upper end of the pivoted jaw so as to hold the pivoted jaw in such a position that it will readily pass over the pipe when the lever 2 is moved into the 55 position shown in Fig. 1 as will be herein fully described.

The head member is provided with a slot extending longitudinally therethrough having oppositely disposed openings therewith in which is mounted a nut 5 in which works 60 the flat threaded shank 4 of the slideable jaw 3, said shank fitting tightly within the slot of the head so as to prevent the same from wabbling and it will be seen that by operating the nut 5 the movable head 3 can be 65 adjusted in respect to the pivoted jaw 7 so that the wrench can be moved to take any size pipe from a one inch pipe to a three inch pipe, but it is, of course, understood that the wrench can be made any size desired, this 70 being the preferred size.

The jaw 3 is provided with a serrated jaw face, the teeth of which extend in opposite directions from those on the pivoted jaw face so that when placed upon a pipe the teeth 75 will engage the same in such a manner that all danger of the pipe turning between the jaws is prevented. It will be also seen that the lever 2 and the pivoted jaw 7 are provided with shoulders 11, 12 adapted to engage 80 the respective ends of the yoke for limiting the movement of the same.

The operation of the wrench is as follows: By moving the lever 2 into position shown in Fig. 1 it is held there by the tension of the 85 spring and at the same time the pivoted jaw is moved into position as shown so that it will be held in an oblique position in respect to the movable jaw 3 whereby the wrench can be readily placed upon the pipe. After 90 the same has been adjusted in the desired position, by pressing the lever downwardly, the beveled end of the lever is brought into engagement with the oblique edge of the pivot jaw so as to cause the same to be forced 95 downwardly into engagement with the pipe as clearly shown in Fig. 3 and as further pressure is applied to the lever the pipe will be securely gripped between the jaws so that it can be readily turned.

By this construction the distance between the movable jaw and pivoted jaw is decreased as the pressure is applied to the lever so as to cause the teeth of the jaws to embed 105 themselves into the pipe so that the danger of the wrench slipping on the pipe is prevented.

What I claim is:—

A pipe wrench comprising a slotted head having an integral yoke, a jaw provided with a shank adjustably mounted in the slot of said head, a pivoted jaw mounted in one end 110

of said yoke provided with an oblique edge having a recess, a lever mounted in the other end of said yoke provided with a beveled end adapted to engage the oblique edge of said jaw, said beveled end being provided with a recess and a bowed spring having angled ends arranged between the end of the lever

and the pivoted jaw the angled ends of said bowed spring fitting within the recess of the respective members.
